UNITED STATES PATENT OFFICE.

GEORGE A. MATTERN, OF BERKELEY, CALIFORNIA.

BATHING SUIT.

Application filed May 6, 1925. Serial No. 28,381.

To all whom it may concern:

Be it known that I, GEORGE A. MATTERN, a citizen of the United States, residing at Berkeley, in the county of Alameda and 5 State of California, have invented certain new and useful Improvements in Bathing Suits, of which the following is a specification.

My invention relates to that class of garments worn by men in athletic or sporting 10 exercises, and especially in swimming. I have, therefore, entitled my invention for the purposes of this application "Bathing suits", though it will be understood that 15 the use of this term herein is meant to include suits for other purposes wherein its novelty may be beneficially applicable.

My invention concerns that portion of the suit or that individual member there- 20 of commonly known as "pants".

Pants or trousers worn by men, have, through long custom, been made to open in the front, beginning at the waist line and ending at the crotch, said opening being 25 controlled by buttons.

In recent years this type of garment, in a much abbreviated leg-length, has been adopted for use as a portion or a member of bathing suits.

30 Due to the rotting effect of water on the thread used to sew on the buttons, and also due to the usage and abuse to which these bathing suits are subjected, both by the wearer and by the caretaker in the bath- 35 house, it is not unusual for the buttons to fall off, thereby threatening embarrassing situations. At the same time, the preference for such a garment, especially as far as appearance is concerned, is likely to 40 continue, and it is not wise to overlook this.

Accordingly, my present invention con- 45 templates, and has for one of its objects, the avoidance of this liability of exposure, by providing a garment having the appear- 50 ance and contour of the usual pants, but which cannot be buttoned or unbuttoned, due to the fact that it is sewn together in the front in such a way as to make it a closed garment, at the same time that the general construction, finish and appearance are identical with those of the pants which are capable of being buttoned or unbut- 55 toned in front.

It is also the custom in the making of pants or trousers to line the waist band

with a non-elastic woven material, which makes it necessary on the part of the customer to get his exact size in the waist measure. Otherwise it will not be a satisfactory fit; and, since the waist measure is so variable in apparently the same sized men, it is difficult to supply a correct fit.

To obviate this necessary precaution my invention further contemplates and has for 60 another object, the provision of a garment with a knit facing at the waist making it very elastic and possible to fit several different sizes of waist measures with one size of pants, the garment being held securely 65 by either a belt or draw string according to the preference of the customer.

The garment made in accordance with my invention is therefore more modest, 70 more comfortable and more acceptable than 75 the customary garment.

My invention consists in the novel garment which I shall now fully describe, by reference to the accompanying drawings in 80 which—

Fig. 1 is a front elevation of the garment.

Fig. 2 is a rear elevation, broken away in part.

Fig. 3 is a sectional detail of the under- 85 lying lap of the front.

Fig. 4 is a sectional detail of the over- 90 lying lap of the front.

Fig. 5 is a sectional detail, enlarged, of 95 the two laps stitched together.

The garment which in its best form is 90 of knitted goods, is of the general type of the pants or trouser member of a bathing suit, and comprises the hip and abdominal portion 1 with waist portion 2 and the ab- 95 breviated leg portions 3 with crotch 4.

The front of the garment from the waist line down to the crotch has, as seen in Fig. 1, the outward appearance of the usual open front pants, one lap of the knit goods over- 100 lying the other, and the outer or overlapping part being further rendered similar in appearance to the usual garment, by the vertically disposed spaced stitching lines, one of which, indicated by the line $a-a$, in Fig. 1, being the edge hem and the other line $b-b$ defining the width of the overlap. There is thus the full appearance external- 105 ly of the usual button-up flap or fly of the customary pants or trousers.

According to my invention, however, these 110 overlapping portions of the garment front are permanently fastened together so that

they cannot be separated, and the front of the garment cannot be opened, that is to say, normally. Accordingly said portions are sewn together; and, as far as the fundamental principle of my invention is concerned, this sewing or permanent connection may be done in any suitable manner.

In practise, I have found the following construction to be satisfactory and workmanlike.

Referring now to Fig. 4, the outer or overlapping portion of the goods is indicated by 5, its edge being turned in at 5'. To the inner side of said portion is fitted a facing strip 6, which at one edge is hemmed to the edge 5' of said portion by the stitching *a—a*, which has been referred to in connection with Fig. 1. The other edge of the facing strip 6 is turned in at 6' on the portion 5.

The inner or underlapping portion of the goods is shown in Fig. 3, at 7.

8 in Fig. 3, is a strip which serves the double purpose of a connecting strip and an inner facing. This strip 8 is doubled or folded on itself, one of its extremities overlapping the outside of the goods portion 7, and hemmed thereto by the stitching 9, and the other extremity overlapping the inside of said portion 7 and hemmed thereto by the stitching 10.

The strip 8, as seen in Fig. 5, extends from these hemmed extremities under the overlapping portion 5 of the goods, and at its fold 8' is secured to said portion 5 and to the end 6' of the facing strip 6 by the line of stitching *b—b* which has been referred to in connection with Fig. 1.

In order to close the two strips 6 and 8, a line of stitching *c*, best seen in Fig. 2, connects them, as shown in Fig. 5, said line extending from the waist line to the crotch in a diagonal to and fro course, which course is of importance in that it leaves the hemmed edge *a—a* of the overlapping portion 5, apparently free at regular intervals, just as if it were buttoned up in the usual manner.

It will also be noted that the closing

the two facing strips 6 and 8, as in Fig. 5, 50 and do not appear on the front of the garment, so that said front as seen in Fig. 1, does not vary in any manner from the appearance of the ordinary pants.

With regard now to the improvement in 55 the waist of the garment, reference is made to Fig. 2. As stated hereinbefore it is usual to inner-face the waist with a non-elastic strip. This I omit, and instead thereof I fold the knitted goods over and inwardly at the top as shown at 11, and hem it by the stitches 12. This gives an elastic waist quite essential in a closed front garment, said waist being also adapted within limits for variation of waist size of the 60 wearers. In this hem fold 11, I seat a draw-tape 13, which may be used to tighten the waist on the user, or if he prefers, he can use a belt, in the loops 14.

I claim:—

1. A garment of the trouser-type having at its front separate terminal portions overlapping, and extending from the waist line towards the crotch; a facing strip lying inside the overlapping portion and stitched thereto along the edge thereof; a folded facing strip stitched at its extremities to the edge of the underlapping portion and stitched at its fold to the overlying portion; and stitching inseparably connecting said facing strips.

2. A garment of the trouser-type having at its front separate terminal portions overlapping, and extending from the waist line towards the crotch; a facing strip lying inside the overlapping portion and stitched thereto along the edge thereof; a folded facing strip stitched at its extremities to the edge of the underlapping portion and stitched at its fold to the overlying portion; and stitching inseparably connecting said facing strips, said last named stitching being vertically directed in a diagonal to and fro course.

In testimony whereof I have signed my name to this specification.
stitches *c* extend only between and connect

GEORGE A. MATTERN.
